(57) **CLAIM**

The ornamental design for a multi EMV chip card, as shown and described.

DESCRIPTION

FIG. 1 is a front perspective view of a first embodiment of a multi EMV chip card showing my new design;

FIG. 2 is a rear perspective view thereof;

FIG. 3 is a rear view thereof;

FIG. 4 is a front view thereof;

FIG. 5 is a front perspective view of a second embodiment of a multi EMV chip card showing my new design;

FIG. 6 is a rear perspective view thereof;

FIG. 7 is a rear view thereof;

FIG. 8 is a front view thereof;

FIG. 9 is a top plan view of the first embodiment, the bottom plan view being a mirror image thereof; and,

FIG. 10 is a left side view of the first embodiment, the right side being a mirror image thereof.

The broken lines are included for illustrating environment that forms no part of the claimed design.
